THOMAS P. FORD, OF NEW YORK, N. Y.

REDUCING-VALVE.

932,262.

Specification of Letters Patent. Patented Aug. 24, 1909.

Application filed November 27, 1908. Serial No. 464,695.

To all whom it may concern:

Be it known that I, THOMAS P. FORD, a citizen of the United States, and a resident of the city of New York, borough of Brooklyn, in the county of Kings and State of New York, have invented a new and Improved Reducing-Valve, of which the following is a full, clear, and exact description.

The invention relates to water distribution and its object is to provide a new and improved reducing valve, more especially designed for high pressure fire systems and the like, and arranged to permit of obtaining variable pressures from a common supply, such as a hydrant, to allow, for instance, the use of several hose, one with a low pressure for inside work and another with a higher pressure for outside work on a burning building. To attain this object use is made of a valve casing having a connection with the hydrant or other source of water supply, and provided with a plurality of outlets for connection with separate fire hose, and main piston valves arranged within the said valve casing for controlling the flow of the water to the said outlets.

Reference is to be had to the accompanying drawing forming a part of this specification, in which the figure is a sectional side elevation of the improvement.

The valve casing A is connected by a nipple B with a hydrant C or other source of water supply, and in the casing A are arranged the valve seats D and E leading to the outlets F and G containing valves F' and G' and adapted to be connected with fire hose for use in burning buildings and the like. On the valve seat D is adapted to be seated the valve H' of a main piston valve H having a piston H² mounted to slide in a cylinder I arranged within the casing A, and the valve seat E is adapted to be closed by a valve J' of another main piston valve J having its piston J² mounted to slide in a cylinder I' arranged within the casing A. The cylinders I, I' are closed at their inner ends and are open at their outer ends, as plainly indicated in the drawings, and the main piston valve H is provided with a passage a for connecting the faces of the piston H² with each other, that is, to allow water which enters the open end of the cylinder I to pass by way of the passage a into the closed end of the said cylinder I. The passage a is provided with a valve seat a' adapted to be closed by the

valve K' of an auxiliary piston valve K, having a piston K² mounted to slide in a cylinder L extending through a suitable stuffing box A' held on the casing A, the outer end of the cylinder L being closed by a cap L'. A spring N presses the piston K² of the auxiliary valve K, to move the valve K' onto the seat a', and the tension of the spring N is adapted to be regulated by the operator by a screw rod O screwing in the cap L' against a washer N' held on the outer end of the spring N. The valve K' of the auxiliary piston valve K is also adapted to be seated on a valve seat P' in a bushing P opening into the inner end of the cylinder L, which latter is provided near its inner end with ports b for the passage of water into the inner end of the cylinder L to press against the piston K² in an outward direction and against the tension of the spring N.

The main piston valve J is also provided with a passage c for connecting the faces of the piston J² with each other, to allow water to pass into the inner end of the cylinder I'. The passage c is provided with a valve seat c' adapted to be engaged by the valve Q' of an auxiliary piston valve Q, having a piston Q² mounted to slide in a cylinder R extending loosely through a stuffing box A² arranged on the casing A. A spring S presses the piston Q², and its tension is regulated by a screw rod T under the control of the operator and screwing in a cap R' closing the outer end of the cylinder R. The inner end of the screw rod T engages a washer S' resting on the outer end of the spring S. The valve Q' is also adapted to be seated on the seat U' of a bushing U held on the main piston valve J and opening into the inner end of the cylinder R screwed to and moving with the main piston valve J, the same as the cylinder R is screwed to the main piston valve H and moves with the same. Ports d are arranged near the inner end of the cylinder R for the passage of water into the inner end of the cylinder R to press against the piston Q².

The operation is as follows: Presuming that the pressure of the supply in the hydrant C is say 300 lbs. and it is desired that the pressure in the outlet F is to be 100 lbs. and that in the outlet G 200 lbs., then the springs N and S are correspondingly adjusted by the operator manipulating the screw rods O and T correspondingly. Now

when the valves F' and G' are closed or the said valves F' and G' are open, and the nozzles in the hose connected with the outlets F and G are closed, then both valves H' and J' of the piston valves H and J are held to their seats D and E by pressure within the casing A passing through the passages a and c into the inner ends of the cylinders I and I', to force the pistons H², J² outward, thus holding the valves H', J' to their seats D and E. When the valves H' and J' are in closed positions, then the valves K' and Q' are seated on their seats P' and U', to allow free passage of the water through the passages a and c to the inner ends of the cylinders I and I'.

Now in case the valve F' is opened or the nozzle of the hose connected with the outlet F is opened, then a reduction of pressure in the inner end of the cylinder L takes place, and consequently the spring N forces the auxiliary piston valve K inward, to move the valve K' from the seat P' onto the seat a', thereby cutting off pressure from the inner end of the cylinder I. The preponderance of pressure on the outer face of the piston H² now moves the latter inward in the piston I, thus shifting the main piston valve H in a like direction and moving the valve H' off the seat D, thus allowing water to flow through the seat D into the outlet F and to the hose and at the pressure of 100 lbs. Now in case the pressure outlet F exceeds 100 lbs., to which the spring N has been set, then the pressure in the inner end of the cylinder I correspondingly increases and moves the piston K² outward against the tension of the spring N, and in so doing the auxiliary piston valve K is shifted outward, to move the valve K' off the seat a' and back onto the seat P', so that water can again pass to the inner end of the cylinder I and push the main piston valve H toward the seat D, and if necessary close the same until the pressure in the outlet F is reduced to 100 lbs. A like operation takes place in case the valve G' or the nozzle on the end of the hose connected with the outlet G is opened, that is, the reduction of pressure in the outlet G causes a like reduction of pressure in the inner end of the cylinder R, so that the spring S moves the auxiliary piston valve Q inward, so that the valve Q' moves off the seat U' and onto the seat c', thus shutting off the pressure from the inner end of the cylinder I'. Now the preponderance of pressure against the outer face of the piston J² pushes the piston valve J into an inward or open position, thus allowing the fluid to pass through the seat E into the outlet G and reducing the pressure to 200 lbs. Now in case the pressure exceeds 200 lbs. in the outlet G and the hose connected therewith, then a like increase of pressure takes place on the liquid in the inner end of the

cylinder R, so that the piston Q² is moved outward against the tension of the spring S, whereby the valve Q' is moved off the seat c' back onto the seat U'. Now pressure from within the casing A can pass by way of the passage c into the inner end of the cylinder I', to act against the piston J² and move the same outward and the valve J' toward or onto the seat E, to reduce the pressure in the outlet G to 200 lbs. When this takes place the valve J' again opens.

From the foregoing it will be seen that by the arrangement described, the two outlets F and G deliver water at different pressures according to the tension given to the springs N and S under the control of the operator.

It is understood that it is frequently desirable to use a fire hose inside of a burning building at a comparatively low pressure, while a hose is used exteriorly with a high pressure and both pressures can be obtained from the same source of supply by the reducing valve described and illustrated in the drawings.

Having thus described my invention, I claim as new and desire to secure by Letters Patent:

1. A reducing valve having a valve casing provided with an inlet for connection with a source of pressure supply and provided with a plurality of outlets, and main piston valves for controlling the flow of the liquid from the said inlet independently and separately to the said outlets. 90

2. A reducing valve having a valve casing provided with an inlet for connection with a source of pressure supply and provided with a plurality of outlets, main piston valves for controlling the flow of the liquid from the said inlet independently and separately to the said outlets, and manually-controlled means for setting the said piston valves to different pressures. 105

3. A reducing valve having a valve casing provided with an inlet for connection with a source of pressure supply and provided with a plurality of outlets, main piston valves for controlling the flow of the liquid from the said inlet independently and separately to the said outlets, the said main piston valves being normally held closed by high pressure of the entering liquid on one side of the piston valve, and means for producing a preponderance of pressure on the other side of the piston valve for opening the same on opening the said outlets. 110

4. A reducing valve having a valve casing provided with an inlet for connection with a source of pressure supply and provided with a plurality of outlets, main piston valves for controlling the flow of the liquid from the said inlet independently and separately to the said outlets, each of the said main piston valves being normally held closed by a high 115

- or a preponderance of pressure on one side of the piston of the said piston valve, and a spring-pressed auxiliary piston valve normally held open against the pressure of the 5 spring by the said high pressure and in communication with the corresponding outlet, to reduce the said high pressure on opening the outlet, to cause the said auxiliary piston valve to shut off the high pressure from the 10 said side of the piston, to move the piston valve into an open position by the preponderance of pressure on the other side of the piston.
5. A reducing valve comprising a valve 15 casing having an inlet for connection with a high pressure source of water supply and provided with a plurality of outlets, valve seats leading to the said outlets, cylinders in the casing, main piston valves having their 20 pistons engaging the said cylinders and their valves engaging the said valve seats for controlling the flow of the water through the said seats to the outlets, each piston having a connection from one face to the other, and 25 an auxiliary piston valve for each main piston valve and having its valve controlling the said connection, one side of the piston of the said auxiliary piston valve being under pressure from the outlet, and a spring
- pressing the other side of the auxiliary piston. 30
6. A reducing valve comprising a valve casing having an inlet for connection with a high pressure source of water supply and provided with a plurality of outlets, valve 35 seats leading to the said outlets, cylinders in the casing, main piston valves having their pistons engaging the said cylinders and their valves engaging the said valve seats for controlling the flow of the water through the 40 said seats to the outlets, each piston having a connection from one face to the other, and an auxiliary piston valve for each main piston valve and having its valve controlling the said connection, one side of the piston of 45 the said auxiliary piston valve being under pressure from the outlet, a spring pressing the other side of the auxiliary piston, and manually-controlled means for regulating the tension of the said spring. 50

In testimony whereof I have signed my name to this specification in the presence of two subscribing witnesses.
